AWNING

Peter John Zeimet, Torrance, Calif.

Application April 5, 1955, Serial No. 499,281

9. Claims. (Cl. 20—57.5)

This invention relates to awnings of the slat or shingle type, wherein a series of edge-lapping, staggered shingles or slats extend in downwardly and outwardly inclined relation from the top of a window casing or the like, so as to shed rain downwardly and outwardly from the window aperture.

A general object of the invention is to provide an awning or canopy utilizing overlapping strips or shingles of wood to obtain an improved ornamental appearance.

A main object is to provide such an awning or canopy of improved construction and arrangement of parts, such as to embody low cost and simplicity combined with sturdiness and durability.

An important object of the invention is to provide such an awning or canopy in a "knock-down" package of parts which can be easily assembled and erected by a home owner, following simple instructions, thus further reducing his cost in obtaining the awning or canopy.

A particular object is to provide a canopy or awning in which a plurality of parallel, overlapping shingles or panel strips are securely held in a frame without the assistance of adhesive, nails, screws or other fastening devices.

Fig. 1 is a perspective view of an awning embodying the invention;

Fig. 2 is a fragmentary perspective view of the cover portion thereof;

Fig. 3 is a vertical longitudinal sectional view of the awning as hung on a wall;

Fig. 4 is a transverse sectional view of the awning, taken on the line 4—4 of Fig. 3;

Fig. 5 is a perspective view of one of the panel strips of the awning cover;

Fig. 6 is a fragmentary detail perspective view of an upper corner of the cover frame;

Fig. 7 is a fragmentary detail longitudinal sectional view of one of the panel strips mounted in a matched course of slots in the cover frame cross bars; and

Fig. 8 is an aside view of a door canopy embodying a modified form of the invention.

Referring now to the drawing in detail, it has been shown in Figs. 1-7 thereof, as an illustration of one form in which the invention may be embodied, an awning that is adapted to be hung over a window or door opening in a vertical wall 10 which is schematically illustrated by the vertical line indicated at 10 in Fig. 3.

The awning comprises, generally, a pair of side members A, of generally triangular outline, and a cover unit B which extends from side to side between side members A and is mounted thereon.

Side members A include respective side rails 11 having at their upper ends, respective fastener loops 12 secured thereto and engageable with hooks 13 that are anchored in wall 10, thereby to suspend the upper end of the awning on the wall. Each side member A also includes a bracket which may take the form of a bar 14, extending between the lower end of the respective side rail 11 and wall 10, attached to the rail as by overlapping

2

and nailing, and attached to wall 10 by means of clips 15.

Brackets 14 function as struts to space the lower ends of side rails 11 outwardly from the wall 10, maintaining the rails at a proper angle of slope downwardly and outwardly from the wall.

Each side member A may also include a series of vertical side panel strips 16, secured at their upper ends, as by nailing, to a strip 17 lying along the outer face of the respective side rail 11 and secured near their lower ends, to bracket bar 14.

Cover unit B comprises a plurality of cross bars including terminal (upper and lower) bars 18, 18', and at least one (preferably only one) intermediate bar 18", 15 together with a plurality of parallel panel strips 19, 19', mounted in the cross bars and sloping longitudinally (parallel to side rails 11) downwardly and outwardly from wall 10.

Cross bars extend horizontally from side to side and 20 are mounted on side members A by having their ends notched to provide reduced end portions 20 that rest upon and are secured to side rails 11 by bolts 21; and shoulders 22 that abut the inner sides of rails 11 to determine the proper spacing between the rails.

25 Each cross bar has a set of slots including an upper row of horizontally aligned slots 23 and a lower row of horizontally aligned slots 23', the slots of the respective rows being staggered as shown. Each slot of one set is matched to corresponding slots of the other two sets 30 so that a course of slots, disposed in a common vertical longitudinal plane, and adapted to receive a respective panel strip 19 or 19', is provided in the assembled frame structure.

35 Panel strips 19 constitute an upper series which, mounted in the upper rows of slots 19, are in laterally spaced relation to one another and in overlapping relation to panel strips 19', the latter being mounted in slots 23', in laterally spaced parallel array.

40 Strips 19, 19' are provided, in their upper faces, with longitudinal grooves 24 which function as water shedding channels. The edges of upper strips 19 are disposed above the center lines of channels 24, so that any overflow from an upper strip will spill into the channels of the lower strips. All rainfall passing through the spaces 45 between the upper strips will of course be also caught by the lower strips.

45 For ventilation, and to minimize decay of the wood in the panel strips, they are vertically separated by spaces, as shown in Fig. 4.

50 The channels 24 provide apertures through slots 23, for drainage of water past the cross bars.

The upper ends of side rails 11 are joined by a header bar 25, to the forward face of which is mounted a cap bar 26. Cap bar 26 has spaced grooves in which the 55 upper ends of panel strips 19, 19' are received.

The invention is particularly characterized by the arcuate longitudinal contour of side bars 11, which causes the cross bars 18, 18', 18" to be disposed with matching slots 23, 23' arranged in staggered relation, i. e., with the slots 23 or 23' of any one course out of alignment.

60 Thus the strips 19, 19', originally straight as shown in Fig. 5, become sprung into longitudinally bowed contour, as shown in Fig. 3. Consequently, the strips will be frictionally locked into cross bars 18, 18', 18", with the outer ends of the strips pressing downwardly against the lower sides the slots in terminal cross bars 18, 18' and with the central portions of the strips pressing upwardly against the upper sides of the slots in intermediate cross bar 18" (Fig. 7).

65 Fig. 8 illustrates how the invention may be embodied in a front door canopy B', adjustable wrought iron braces 14',

the canopy being arched upwardly as contrasted to the downward arching of the cover B of Fig. 1.

In assembling the awning or canopy, the cross bars are first bolted to the side rails to constitute a cover or canopy frame; hanger hooks 13 are attached to the wall; the frame is hung on the hooks; and side members A, or brackets 14' are then installed to support the cover or canopy in outwardly sloping position.

The panel strips 19, 19' are then pushed through the slots 23, 23' of their respective courses, being inserted at the lower outer end of the frame, through cross bar 18' and advanced to proximity to cross bar 18", then sprung upwardly and pushed through the proper slot in bar 18", and then advanced to upper cross bar 18, sprung upwardly, and pushed through the proper slot in that bar.

I claim:

1. An awning of wood construction: a relatively rigid frame structure comprising a plurality of laterally spaced supports; a plurality of cross bars, including two terminal cross bars and at least one intermediate cross bar, extending from side to side between said supports and mounted thereon; and a plurality of longitudinally extending parallel panel strips extending between and mounted in the respective cross bars; said cross bars having respective sets of slots, each slot of one set being related to corresponding slots of the other sets to constitute a longitudinally extending course of matched terminal and intermediate slots disposed in a common surface of single curvature about an axis parallel to said cross bars and to which said cross bars are normal, and staggered so that an intermediate slot is out of alignment with the terminal slots of the course; each panel strip extending through the slots of a respective course and being sprung from its normal longitudinal contour into a longitudinally bowed condition as the result of confinement in the staggered slots of the respective course, and thereby having frictionally gripping engagement with opposite walls of alternate slots of the respective course, thus being secured against longitudinal displacement from its installed position.

2. An awning as defined in claim 1, wherein each set of slots consists in upper and lower rows of horizontally aligned, laterally spaced slots, with the slots of one row in staggered relation to the slots of the other row; and wherein said panel strips consist in corresponding groups of spaced parallel lower panel strips and spaced parallel upper panel strips covering the spaces between the lower strips.

3. An awning as defined in claim 2, wherein all of said panel strips have their upper faces grooved to provide rain-shedding channels, and wherein said supports are constructed for supporting said cross bars and panel strips in downwardly and outwardly sloping extension from a vertical wall to which said supports are adapted for attachment.

4. An awning of wood construction: a relatively rigid frame structure comprising a plurality of laterally spaced side members having means for attachment thereof to a vertical wall of a building and including respective longitudinal side rails supported in positions sloping downwardly and outwardly from said wall when attached thereto, and a plurality of cross bars, including two terminal cross bars and at least one intermediate cross bar, extending from side to side between said side rails and mounted thereon; and a plurality of longitudinally extending parallel panel strips extending between and mounted in the respective cross bars; said cross bars having respective sets of slots, each slot of one set being related to corresponding slots of the other sets to constitute a longitudinally extending course of matched terminal and intermediate slots disposed in a common surface of single curvature about an axis parallel to said cross bars and

to which said cross bars are normal, and staggered so that an intermediate slot is out of alignment with the terminal slots of the course; each panel strip extending through the slots of a respective course and being sprung from its normal longitudinal contour into a longitudinally bowed condition as the result of confinement in the staggered slots of the respective course, and thereby having frictionally gripping engagement with opposite walls of alternate slots of the respective course, thus being secured against longitudinal displacement from its installed position.

5. An awning of wood construction: a relatively rigid frame structure comprising a plurality of laterally spaced side members having means for attachment thereof to a vertical wall of a building and including respective longitudinal side rails supported in positions sloping downwardly and outwardly from said wall when attached thereto, and a plurality of cross bars, including two terminal cross bars and a single intermediate cross bar, extending from side to side between said side rails and mounted thereon; and a plurality of longitudinally extending parallel panel strips extending between and mounted in the respective cross bars; said cross bars having respective sets of slots each consisting in upper and lower rows of horizontally aligned laterally spaced slots, with the slots of the respective rows in staggered relation to one another, said panel strips consisting in corresponding groups of spaced parallel lower panel strips and spaced parallel upper panel strips covering the spaces between the lower strips, each slot of one set being related to corresponding slots of the other sets to constitute a longitudinally extending course of matched terminal and intermediate slots disposed in a common surface of single curvature about an axis parallel to said cross bars and to which said cross bars are normal, and staggered so that the intermediate slot is out of alignment with the terminal slots of the course; each panel strip extending through the slots of a respective course and being sprung from its normal longitudinal contour into a longitudinally bowed condition as the result of confinement in the staggered slots of the respective course, and thereby having frictionally gripping engagement with opposite walls of alternate slots of the respective course, thus being secured against longitudinal displacement from its installed position.

45 6. An awning as defined in claim 5, wherein each side member includes a fastener to attach the upper end of its side rail to the wall in suspended condition, and a bracket attached to and extending generally horizontally from its lower end to the wall, abutting the wall, and operating 50 as a strut to support the lower end of awning away from the wall.

7. An awning as defined in claim 6, including a cap bar extending horizontally from side to side above and adjacent the uppermost cross bar and having grooves in 55 which the upper ends of the panel strips are received.

8. An awning as defined in claim 7 wherein all of said panel strips have their upper faces grooved to provide rain-shedding channels.

9. An awning as defined in claim 8, wherein said side 60 members include side panel strips extending vertically between said side rails and said brackets and secured thereto to provide side enclosure in the awning.
